(57) **CLAIM**

(51) LOC (7) Cl. **07-05**

The ornamental design for a steam generating base, as

(52) U.S. Cl. **D32/73**

shown and described.

(58) Field of Search D32/68, 71, 73;

DESCRIPTION

38/75, 77.6, 96, 141, 142; 219/246-252,

FIG. 1 is a perspective view of a steam generating base in
accordance with the present design;

259; 248/117.1, 117.2, 117.3; 392/394,

FIG. 2 is a left side elevational view thereof;

404

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

FIG. 1 is a perspective view of a steam generating base in
accordance with the present design;
